[57] **ABSTRACT**

A method of, and apparatus for, compression forging of components in which a bar section is pre-shaped by upsetting in a direction along its axis. The pre-shaped bar section is then supported by its ends between a pair of die faces and is deformed to a shape close to its final shape by transverse flow pressing. The shaped bar section is then ejected from the dies and is transferred to means for removing burrs from the bar section. Preferably at least one of the die faces is sprayed with a cooling fluid after the shaped bar section is ejected.

**METHOD OF AND APPARATUS FOR
COMPRESSION FORGING OF COMPONENTS**

The present invention relates to a process of, and apparatus for, the compression forging of a blank in the form of a bar section.

A particular, but not exclusive application of the invention is in the production of components which have delimiting faces variously spaced from the press axis, in particular forgings for articulated cross-pieces, "tripods", T-irons, and the threaded pipe elbows.

The rational manufacture of such elements had hitherto still involved considerable disadvantages. In one known process for the manufacture of the articulation crosspieces required for universal joints (knuckle joints), work commences from a rectangular bar out of which a predetermined number of articulation crosspieces (preferably four) are first of all pre-pressed, in a row disposed side-by-side, the crosspieces then being punched out. With this method, there is produced a relatively large amount of material waste, since of the original rectangular bar only the portions punched-out in the shape of cruciform elements can be used. Furthermore for the simultaneous punching-out of the four crosspieces (cruciform elements) four different dies have to be used, so that the articulation crosspieces exhibit dimensional deviations which, although small, are nevertheless noticeable and which are a source of difficulty during the subsequent machining and also during operation of the universal joint. Furthermore, the articulation crosspieces thus manufactured have a burr (or flash) following the entire peripheral line and located in particular at the end faces of the cross arms, which makes subsequent machining difficult and costly. To this must be added the fact that, with the conventional manufacturing process, the grain of the material extends parallel in all sections of the articulation crosspiece, so that the finished shaped component exhibits a diminished degree of toughness or reduced stress-withstanding properties in predetermined directions of an applied force.

According to one aspect of the present invention there is provided a process for the compression forging of components from blanks in the form of bar sections, which process includes pre-shaping a bar section by upsetting the bar section in a direction along its longitudinal axis, and supporting the upset bar section axially between co-operating dies and deforming the upset bar section to form a shaped component, whose shape is close to its final shape by transverse flow pressing of the upset bar section between the co-operating dies.

In one form of the process in accordance with the present invention a blank is, after being severed from the bar, retained held against an upsetting means in a first deformation station between a holding means which is displaceable coaxially with respect to the press ram and is under resilient pressure, and is then, by axial upsetting with the aid of the press ram, preshaped to a pressing. The pressing is then introduced, in a second deformation station, between two die halves which are disposed opposite each other and is, by a relative movement of the die halves and by means of "transverse flow" pressing deformed to a forged component similar to the final shape.

Thus, this process permits rational manufacture of the shaped components concerned, by automatic methods at a higher production rate, in a plurality of defor-

mation stages following one after the other, this being something which hitherto had not been possible. In fact, it was considered that the problems connected therewith, such as the dimensional accuracy of the shaped components, the controlled discharge of the numerous sheared-off small burrs, the limitations of die wear, and the cooling of the matrix-side die halves, could not, in view of the enormous material stressing and the high production rate required, be solved together. The process in accordance with the present invention affords this solution and in this way permits a considerable increase in production since, now, on an apparatus operating in accordance with the invention approximately 120 pieces per minute can be produced as compared with the hitherto obtaining production of at maximum approximately 20 pieces per minute. Since all the shaped components travel through the same dies, they are absolutely identical and can be further machined without difficulty. Furthermore, however, also the grain configuration of the material resulting from deformation may be considered to be ideal in the case of the present invention. According to the above-mentioned known process, the grain configuration is, for example in the manufacture of universal joints, practically parallel to the common axis of two articulation cross arms disposed opposite each other. Whereas in the process according to the present invention, the grain run in the blank is, before deformation, parallel to the press axis and, during the upsetting step, the fibers are "bulged out" (see FIGS. 2 and 5 of the accompanying drawings) thus imparting an extraordinary degree of toughness to the material.

The intentional burr (or flash) produced during deformation may be considered to constitute a material buffer for compensating the volume differences in the bar section resulting from tolerance variations in the raw material. In the case of articulation crosspieces formed with an axial bore (FIGS. 17 and 18 of the accompanying drawings) the burr formation can be avoided because the excess material may be taken up in a portion to be punched out to form an aperture. It is also possible to restrict the aforementioned volume variations to a minimum from the outset, by rough turning or drawing the rolled bar stock. However, the formation of a burr will in many cases be unavoidable for reasons connected with costs and manufacturing techniques. In these cases, the process according to the invention may be supplemented by the arrangement whereby the two die halves are, at the points corresponding to the recesses in the shaped component (in view of the burr formation) approached to each other only up to a predetermined spaced relationship, the shaped component being ejected out of the die by at least one ejector and displaced by means of a transverse conveying device into a holding-on position before a burr removing station, whereupon the burr is sheared off in the burr-removal station between a female punching die and a male punching die, both the shaped component and also the sheared-off burr being retained until they are able, after the return travel of the male punch die to drop down unhindered.

According to a second aspect of the present invention there is provided apparatus for the compression forging of components from blanks in the form of bar sections, comprising means for pre-shaping a bar section by upsetting it in a direction along its longitudinal axis, and means for supporting the upset bar section ax-

ially between co-operating dies having a shape close to the final shape of the component and for applying a pressure to the dies to deform the upset bar section into the dies by transverse flow pressing.

In one embodiment of the apparatus made in accordance with the present invention a blank severed from a bar is fed, in chronological sequence by a transverse conveying means, to an upsetting station and from the latter to a deformation station having a die. The upsetting station has a ram mounted for sliding in the pressing direction, and coaxial thereto, a fixed counter-holding means arranged opposite in spaced relationship, a holding pin resiliently pressed in the direction of the counter-holding means being mounted coaxially and for displacement in the ram. A female die of the deformation station has a central ejector mounted for coaxial sliding therein, and the coaxially oppositely arranged ram or male die has a holding pin mounted for coaxial sliding movement therein and is resiliently urged in the direction of the female die. The axial movement of the ejector relative to the ram or male die movement is so synchronized that the pressing first of all adopts a holding-on position between the holding pin and the ejector and, subsequently, due to axial advance of the male die and corresponding withdrawal of the ejector, is adapted to be pushed into the die mound and deformed. In the female die body there is arranged, for each of the shaped component sections projecting laterally outwardly, a controlled ejector pin mounted for sliding parallel to the central ejector. Furthermore the two die halves disposed opposite each other are embraced by an annular matrix sealing the said halves off radially.

Preferably a burr-removing station is provided at which there are arranged tool elements provided with burr-removal edges, the female die being provided with a holding pin for retaining the shaped component in a holding-on position, there being furthermore provided in the ram body of the burr-removal station, for each burr on the shaped component to be punched off, a holding pin mounted for axial sliding movement and subjected to the influence of a resilient means which presses the holding pin during and after the burr-removal step against the associated burr and presses the latter against a front face, facing it, of the female die.

The ejector which is mounted in the deformation station and has the shape of an ejector pin may have a blind aperture bore connected to a source of coolant, there being formed in the walls of the ejector pin at least one passage bore extending practically transversely of the blind aperture bore and debouching into the same, to serve for the outflow of coolant on to the female-die-side die faces.

With this arrangement, there is advantageously arranged within the zone of movement of the female-die-side ejector pin a resilient means pressing the ejector pin back to the forward edge of the female die after reaching the front dead center. The resilient means may for example be a cup spring assembly, the ejector pin having a collar rigidly connected therewith and which, towards the end of the ejection movement, impinges on the cup spring assembly and biases the latter.

In a further embodiment, the ejector has a cylindrical section formed with a cooling bore and a sleeve mounted for sliding on the periphery of the said section, the sleeve being connected via two ejector pins of

varying diameter arranged in a stepped bore with an actuating rod, and the female-die-side pin projecting, before commencement of the ejection step, to a predetermined extent into the bore of the thicker pin so that, due to the movement of the actuating rod first of all only the sleeve is advanced by the aforesaid amount and then the sleeve with the ejector section is advanced to a further extent.

Embodiments of the invention will now be described, 10 by way of example, with reference to the accompanying drawings, in which:

FIG. 1 shows, as a simplified sectional view, an upsetting station into which a rod section to be deformed has just been introduced,

FIG. 2 shows the upsetting station according to FIG. 1 shortly after completion of the upsetting step,

FIG. 3 is a diagrammatic sectional view of a deformation station, showing the pre-upset pressing shortly after withdrawal of conveying tongs or grippers,

FIGS. 4 to 8 show the individual processing phases through which the pressing passes in the deformation station according to FIG. 3,

FIG. 9 is a simplified sectional view of a burr-removal station, showing the blank shortly before initiation of the punching step,

FIGS. 10 to 12 show individual phases through which the blank passes in the de-burring station, in chronological sequence,

FIGS. 13 and 14a to 14c each show a variant of the 30 deformation station shown in FIG. 3, and

FIGS. 15 to 26 show examples of shaped components which may be produced on the device illustrated.

In the drawings, which as an example of an embodiment show the manufacture of an articulation cross-piece according to FIGS. 15 and 16 on an automatic transverse conveying press, the rod section sheared off from round stock has been designated 1. In the case of the transverse conveying press illustrated, the round bars which have a length of 4 to 6 m. are first of all pushed on rollers through a heating means, heated to forging temperature and fed to the subsequent shearing or severing operation. There, sections of predetermined length, corresponding to the required blank weight, are severed transversely of the machine axis. A shear blade 2 and a special holding finger 3 convey the rod section in the direction of the arrow 4 into position before the upsetting station shown in FIG. 1. The upsetting station has a ram or male die 6 mounted for sliding movement in the pressing direction, i.e. in the direction of the arrow 5, and also disposed coaxially opposite the ram a stationary upsetting plate 7. The ram 6 installed in a ram holder 8, with interpositioning of a sleeve or bush 9, may be driven for example by means of a cam disc or a crank mechanism; this drive is immaterial in the present connection and has therefore not been shown.

A retaining or holding pin 10 is mounted for coaxial sliding movement within a stepped bore in the ram 6. The holding pin 10 is subjected to the influence of a spring 11 tending continuously to press it into the position shown in FIG. 1. In this position, the shear blade 2 which is shown in broken lines has, together with the holding finger 3 after release of the bar section 1, been withdrawn from the latter and the bar section is then retained by spring pressure between the holding pin 10 and the front face of the upsetting pin 7. This intermediate position is necessary in order to ensure entirely

satisfactory withdrawal of the shear blade 2 and the holding finger 3 before initiation of the upsetting step.

The fixed upsetting plate 7, mounted on an anvil 12 is retained in a mounting sleeve 13. The upsetting plate may be supplied with coolant via a central bore 14.

Whilst the shear blade 2 has, together with the holding finger 3, been released from the section 1 and has travelled back into its starting position for shearing-off and engaging the next bar section, the ram 6 is advanced in the direction of arrow 5. As this takes place, the holding finger 10 is pushed, accompanied by compression of the spring 11, further into the ram 6. As soon as the front face 6a of the ram is flush with that of the holding finger 10, i.e. on impingement thereof on the section 1, also the holding finger 10 impinges on a stop and the bar section 1 is then pressed by the ram 6 and the holding finger 10, jointly, against the upsetting plate 7. During this procedure, the end phase of which is shown in FIG. 2, the bar section is deformed to afford a barrel-shaped pressing 15 having precisely predetermined dimensions. After completion of this upsetting step, the ram holder 8, with the ram 6, is withdrawn in the direction of arrow 16, whereas the holding finger 10 still retains its position shown in FIG. 2 and holds the pressing 15 fast, until the latter is, for the purpose of further transport to the deformation station, engaged by a pair of grippers (not shown).

FIG. 3 shows the deformation station in which the pre-upset pressing 15 is put into the desired shape by means of a transverse flow pressing step. The deformation station has a ram 17 into the front face of which a die half 18a has been machined. A spring-biassed holding pin 19 is mounted for sliding movement within the ram 17, coaxial thereto. A stationary female die 20 is disposed opposite the ram or male die 17. A die half 18b is provided in the front face of the female die 20 which faces the ram or male die 17. The die 20 is retained in a female die holder 22 by an annular matrix 21 interposed therebetween. The die 20 is formed with a central bore within which an ejector pin 23, coaxial with the ram 17 is slidable. Furthermore, there is mounted in the female die 20 a plurality of ejector pins 24 the function of which will be described later. All the ejector pins 23 and 24 are connected with a sliding piston or plunger 25 controlled by a cam disc. The latter is unimportant for an understanding of the idea of the invention it has therefore not been shown.

The central ejector pin 23 is formed with a blind aperture bore 23a connected to which are transversely extending outflow ducts 25, 26, 27, 28 and so on. The central bore 23a is connected to a source of coolant.

In the position shown in FIG. 3, the pressing 15 has, after being introduced by the transverse conveying grippers (not shown) in the direction of arrow 29, been received by the facing end faces of the ejector pin 23 and of the holding pin 19. The pressing 15 is thus retained in its position according to FIG. 3, so that the grippers have been able to open and return to the upsetting station. Then, the deformation step proper is initiated, the ram or male die 17 being first of all displaced in the direction of arrow 30 (FIG. 4) towards the female die. As soon as the die half 18a impinges on the facing end face of the pressing 15, also the holding pin 19 reaches a position wherein its end face 19a is flush with the face of the die half 18a. On further advance of the ram 17 in the direction of the arrow 30, first of all the central ejector pin 23, and therewith via

the slide piston 25 also the ejector pins 24, are pushed back into the position shown in FIG. 4. At this instant, i.e. on impingement of the barrel-shaped pressing 15 on the female-die-side (or matrix side) die half 18b, the "flow pressing" step commences.

As FIGS. 5 and 6 show, the pressing 15 is so pressed-in between the ram 17 and the female die 20 that it completely fills the two die halves 18a and 18b. In this connection, special attention should be given to the grain run of the pressing material indicated in FIG. 5, which, in contradistinction to what obtains with hitherto known manufacturing methods, guarantees an especially high degree of resistance to stressing and in particular toughness of the final product.

As soon as the ram 17 has reached its front dead center according to FIG. 6, the pressing is completely shaped to afford an articulation crosspiece blank 31. In this connection, it should be observed that the ram 17 has been able to approach the female die 20 only up to a position having reciprocal spacing a. For an understanding of this step, which is provided in view of burr formation, reference will first of all be made to the embodiment shown in FIGS. 15 and 16 of the articulation crosspiece to be manufactured.

The crosspiece (or cruciform member) designated 31 as a whole and whereof FIG. 16 shows a plan view and FIG. 15 a section taken along the line XV—XV of FIG. 16, is a shaped component the individual section of which exhibit varying radial spacings relative to the axis M. One of the spacings has been designated r by way of example in FIG. 16, whereas the other has been designated R. This varying radial dimensioning of the various shaped component sections has, in the case of "cross flow" pressing on automatic transverse conveying presses hitherto been considered to represent a very considerable obstacle which could not be overcome using conventional means. In the case of the above-described process, there is left at the interspaces between the shaped component sections of greater radial extent (R), in the deformation phase, a burr 32 which is sheared-off in a subsequent de-burring operation.

After deformation has been effected, the ram 17 is lifted off from the female die 20 in the direction of arrow 33. Meanwhile, the holding pin 19 retains its position, under the influence of the spring acting on it and ejects the crosspiece blank 31 out of the die half 18a of the ram 17. The blank 31 is thus retained by the holding pin 19 in the female-die-side die half 18b.

On further travel-back of the ram 17 in the direction of the arrow 33 (FIG. 7) however, the holding pin 19 impinges through the agency of its oblique shoulder 19a on a corresponding shoulder in the central bore of the ram 17 and, from this instant on, is entrained by the ram 17. Then, the female-die-side ejectors 23 and 24 are able to eject the crosspiece blank 31 out of the female-die-side die half 18b and to surrender it to the transport grippers (not shown) which are in the readiness position. In this position, which is shown in FIG. 8, the mouths of the transversely extending outflow ducts 25, 26 and 27 of the central ejector pin 23 are freed and the cooling water entering through the central bore 23a is able to flow out in controlled manner onto the female-die-side die half 18b. It should be observed that the position and angle of inclination of each duct is so selected that the emerging coolant jets impinges precisely on those parts of the female die which are most stressed and therefore also hottest. In this

way, also inner wall portions of the annular matrix 21 may be cooled. Furthermore, according to a provision of the embodiment described there are provided also in the annular matrix 21 coolant ducts 34 which are fed from an annular conduit 35 and direct the coolant also on to the female-die-side die half 18b.

Then, the female die-side ejector pins 23 and 24 are pushed back, by a spring 36 (FIG. 8) acting on the ejector pin 23 in the direction of arrow 37, to such an extent that the end faces of the ejector pins reach the position shown in FIG. 3 and are therewith ready for receiving the next pressing.

Then, the articulation crosspiece blank 31, which has the shape shown in FIGS. 15 and 16, still requires to be de-burred. For this purpose, it is first of all put, by a pair of grippers which have been made ready into the de-burring station shown in FIG. 9. The de-burring station has a female punching die 37 and a male punching die 38. In this case also, recesses 38a or 38b corresponding to the shape of the articulation crosspiece blank 31 have been provided, but projecting punching elements have been provided at the points to be de-burred, so that the burrs (or flashes) 32 are sheared off by the sharp punching edges 39. On arrival at the de-burring station, the articulation crosspiece blank 31 is first of all received by a spring-biased holding pin 40 and an ejector pin 41 which is also loaded by a compression spring 41a, whereupon the transverse conveying grippers (not shown) are able to open and to return to the deformation station. The punching ram 38 then travels in the direction of arrow 42, thereby pushing the blank 31 into the female-die-side recess 38b.

In the position which has now been reached (shown in FIG. 10), the holding pin 40 and the ejector 41 are, overcoming the corresponding spring forces, pushed into the male die or the female die.

Arranged for axial sliding movement in the male die 38 there are, in addition to the holding pin 40, four further holding pins 43 which are somewhat smaller in diameter. The angular position of these holding pins, which are also loaded by springs 44, and the spacing thereof from the central male die axis are so selected that the end faces of these four holding pins impinge, in the front dead center of the male die, precisely on the four burrs 32 of the articulation crosspiece blank 31 (FIG. 10). The small, spring-biased holding pins 43 thus retain the burrs 32 during the burr-removal step, thereby considerably contributing to smooth development of this step.

As soon as the male die has passed beyond (in the direction of arrow 42) the position shown in FIG. 10, the burrs are sheared off and the blank is, with the female die and against the action of a spring 45, pushed into the female die housing. In this connection, it is above all significant that the burrs 32 are, also after shearing-off, pressed by the holding pin 43 against the front face of the female die and therewith prevented from dropping down (FIG. 11).

The female die, designated 37 as a whole, consists, in the case of the present embodiment, of a female die section 37a carrying the die half 38b and also a centring body 37b. A person skilled in the art will be able to vary this construction, which has been selected here purely by way of example, in many ways.

After completion of the de-burring step, the male punching die 38 is withdrawn in the direction of arrow 46 (FIG. 12).

The holding pins 43 still clamp the burrs 32 for a short time against the end-face side of the centring body 37b of the female die and simultaneously the central holding pin 40 still retains the de-burred articulation crosspiece 47 fast in the female punching die. At a subsequent instant in time, the spring 45 urges the female die-side ejector pin 41 forwardly, thereby releasing the articulation crosspiece 47 out of the die half 38b of the female die 37. By means of the collar 41a provided on the ejector pin 41, the female punching die is, shortly after ejection of the articulation crosspiece 47, returned into its starting position shown in FIG. 9. The articulation cross-piece 47 and the burrs or flashes 32 fall, after withdrawal of the holding pins 40 and 43, on to a conveyor belt (not shown) travelling past below the same, and are subsequently sorted in separate containers.

A constructional variant of the deformation station shown in FIGS. 3 to 8 is illustrated in FIG. 13. The mode of illustration corresponds to the phase according to FIG. 6, so that here the deformation operations according to FIGS. 1 to 5 have already taken place. The only deviations from the embodiment described there are to be found in the deformation station itself. In this case, a press ram or male die 49 according to FIG. 13 may be designed similarly to or in the same manner as the ram or male die designated 17 in FIGS. 3 to 8. A female die body 50 provided with the corresponding die half at its front side is mounted in a female die holder 51, an annular matrix 52 being inserted in the front section of the female die holder. Adjacent the rear end faces of the female die body 50 and the female die holder 51 is a stationary securing ring 53 having a pressure member 54. Arranged for axial sliding movement, in a central bore extending through the pressure member 54, the securing or tensioning ring 53 and the female die body is an ejector rod built up from several sections and designated 55 as a whole. The ejector rod consists substantially of a first section 55a connected with a drive means (not shown), the two central sections 55b of slightly larger diameter, and also the cooling and ejector section 55c. The aforementioned central bore is comprised, as FIG. 13 clearly shows, in its upper portion of three circular-cylindrical sections of stepwise increasing cross-section. Arranged in the section of maximum diameter is a cup spring assembly 56 concentrically surrounding the cooling and ejector section 55c.

Here also, the ejector rod 55 is again provided with a coolant feed conduit 57 supplying the female-die-side die half, via transverse bores 58, with a cooling medium.

In the processing phase illustrated, the male die or ram 49 is in its front dead center. The articulation crosspiece blank is thus finish-shaped and must now, for further transport to the de-burring station, be ejected out of the die and transferred to the transverse conveying grippers. For this purpose, therefore, the male die or ram is first of all lifted off in the direction of arrow 59 from the articulation crosspiece blank 31, whereupon the ejector rod 55 is, under the influence of the drive means (not shown), for example a control cam, advanced in the direction of arrow 60. Thereby, the articulation crosspiece blank 31 is pushed out of

the die half of the female die 50 into the transverse conveying grippers which are ready to receive it and, simultaneously, the heated female die elements are sprayed with cooling medium via the transverse bores 58.

During the last-described movement of the ejector rod 55, naturally also the central sections 55b travel forwardly in the direction of the arrow 61, thereby compressing, during the last section of their travel path, the cup spring assembly 56. As soon as the ejector rod 55 has reached its front dead center and has therewith transferred the articulation crosspiece blank 31 to the transverse conveying grippers, the drive means thereof frees the return travel movement oppositely to the direction designated 60. This means, however, that the ejector rod 55, which had compressed the cup spring assembly 56 at least by the amount X, is now pushed back by the same amount. Then, the transverse conveying grippers are able to transport the articulation crosspiece blank 31, without hindrance, to the de-burring station and the deformation station is able to receive the articulation crosspiece blank arriving from the up-setting station.

Further processing of the articulation crosspiece blank is then effected in accordance with FIGS. 9 to 12.

On using the above-described embodiment of the deformation station according to FIG. 13, the articulation crosspiece blank 31 is thus first of all released by the ejector section 55c out of the female-die-side die half, whereupon the end face of the ejector section 55c must, on travel-back thereof, be released from the outer face of the articulation crosspiece blank 31. As this takes place, however, it is possible that the articulation crosspiece blank may remain adhering to the ejector section 55c and be drawn by the latter, on return travel movement thereof, back into the female die-side die half. This disadvantage is avoided on using the following embodiment described with reference to FIGS. 14a to 14c.

In the case of this embodiment, the construction of the ram or male die 49 again corresponds, unchanged, to what is shown in FIGS. 3 to 8 and 13. On the female die side, the deformation station again has a female die body 62 and also a female die holder 63 and a central annular matrix 64. Adjacent the female die body 62 is a securing ring 65 and also a pressure member 66. Arranged for axial sliding movement in the pressure member 66 and also in a pressure member 67 arranged within the securing ring 65 are three ejector pin pairs 68a, 68b, each being offset through 120° relative to each other. A central ejector pin 69 also mounted for sliding in the pressure member 66 bears, through the agency of its lower, collar-shaped section 69a, on the facing end face of the pressure member 67. Secured in a wedge or key 70 arranged between the pressure member 67 and the securing ring 65, through the agency of a locking pin 71, is the ejector section 72. Mounted for sliding movement at the periphery of the ejector section 72 is a lifting sleeve 73. The lifting sleeve has, in its rear portion, a collar 73a and is formed in its central portion with a recess 73b for receiving and further conveying of the coolant.

The rear section of the ejector pin 69 contacts a sliding member 80 slidable in a central bore of the ejector actuating rod 79 and loaded by a compression spring 81.

A coolant feed bore 75 extends through the central ejector pin 69, the pressure member 67 and the ejector section 72, so that the cooling medium is able to flow out via this bore through transverse bores 76 arranged in the ejector section, through the annular chamber 73b and through the outlet bores 77 arranged in the lifting sleeve.

In the position shown in FIG. 14a, the male die or ram 49 has reached its front dead center; the deformation step is completed and the male die is then withdrawn in the direction of arrow 78. Simultaneously the actuating rod 79 displaces the ejector pins 68a and 68b by the amount x forwardly, the lifting sleeve 73 being meanwhile displaced forwardly by the same amount, via a disc 82. During this relatively short movement, the articulation crosspiece blank 31, which, in the case of the example of embodiment selected corresponds to what is shown in FIGS. 17 and 18 is released out of the female die body 62.

During the movement described of the lifting sleeve 73 by the amount x, the result is simultaneously achieved that the front edge of the lifting sleeve 73 is flush with that of the ejector section 73; the end face of the ejector section 72 is thus, as appears from FIG. 14b, withdrawn by the amount x from the face adjacent it of the articulation crosspiece blank 31. This position of the ejector section 72 relative to the articulation crosspiece blank 31 must be reached, in order that, after travel out of the female die, subsequent transverse conveying of the articulation crosspiece blank shall not be hindered by the front edge of the ejector section 72.

During the aforesaid stroke through distance x, the ejector pin 69 retains its original position as shown in FIG. 14a and presses the slide member 80, meanwhile compressing the spring 81, into the central bore of the actuating rod 79. The collar 69a of the ejector pin 69 is, under the action of the spring 81, continuously pressed against the facing end face of the pressure member 67, so that a continuous feed flow of coolant through the central bore 75 in the ejector section 72 is assured.

As soon as the actuating rod 79 continues its movement in the direction of arrow 83 in FIG. 14b, the ejector pin 68a impinges at its end face at 84 on the pressure member 67 and pushes the latter, together with the ejector section 72 secured by the wedge 70 and the locking pin 71, the lifting sleeve 73 and the articulation crosspiece blank 31, forwardly by the amount B. Therewith, the crosspiece blank 31 is located completely externally of the female die (FIG. 14a) and can be received by the grippers (not shown) which are in the readiness position and transported to the next processing station.

The overall displacement, which has thus taken place, of the crosspiece blank 31 by the amount A (FIG. 14a) thus corresponds to the sum of the two individual strokes B and x.

After completed ejection of the crosspiece blank, the ejector section 72 and the lifting sleeve 73 remain in their position shown in FIG. 14c until they are again pushed back by the ram, together with the pressing designated 15 in FIG. 3. Meanwhile, the lifting sleeve 73 is, at the end of the ram stroke, pushed further back by the value x by the deforming articulation crosspiece material which completely fills the female die-side die half.

FIGS. 15 to 25 show some examples of crosspieces which may be manufactured in accordance with the above described process. FIGS. 15 and 16 show an articulation crosspiece blank as also shown in FIGS. 1 to 13. FIGS. 17 and 18 again show an articulation crosspiece blank formed additionally, however, with an aperture in its center. The aperture may also be punched-out in the punching station.

FIGS. 19, 20, 21 and 22 show various tripods, i.e. three-armed articulation cross-pieces, which may be manufactured in accordance with the process according to FIGS. 1 to 13. In accordance with the same process, it is also possible to manufacture threaded tubular elbow means according to FIGS. 23 and 24 and the T-iron according to FIGS. 25 and 26.

Various embodiments of the apparatus made in accordance with the present invention are possible within the scope of the appended claims.

I claim:

1. Process for the compression forging of components from blanks in the form of bar sections, comprising the steps of:
  2. pre-shaping a bar section by upsetting said bar section in a direction along its longitudinal axis;
  - b. supporting the upset bar section axially between co-operating dies and deforming the upset bar section to form a shaped component whose shape is close to its final shape by transverse flow pressing of said upset bar section between said cooperating dies;
  - c. transferring said shaped component to a third station whereat burrs are removed from said shaped component by holding said shaped component in shaped members and shearing the burrs from said component using co-operating male and female punching dies; and
  - d. retaining said shaped component and the sheared-off burrs in position until each male punching die has returned to its starting position, whereafter said shaped component and said sheared-off burrs are released.
2. Apparatus for the compression forging of components from blanks in the form of bar sections, said apparatus comprising, in combination:
  - a. means at one station for pre-shaping a bar section by upsetting it in a direction along its longitudinal axis;
  - b. a set of co-operating male and female die halves each having a shaped end having a shape close to the final shape of the component to be forged at another station;
  - c. means for supporting the upset bar section axially between said set of dies;
  - d. a resiliently mounted retaining means mounted coaxially in the male die half so as to be relatively moveable thereto;
  - e. an ejector slidably mounted coaxially in the female die half;
  - f. a controlled ejector pin movable parallel to said ejector;
  - g. pressure applying means for applying a pressure to at least one die half of said co-operating die halves so that said upset bar section is deformed by transverse flow pressing into a shaped component; and
  - h. an annular matrix positioned to enclose the die halves when closed by said pressure applying

means.

3. Process as defined in claim 1, further comprising the step of (e) spraying at least one of said co-operating dies with a coolant.

5. 4. Process as defined in claim 1, in which said pre-shaping step takes place at a first deforming station at which said bar section is resiliently retained against an upsetting means and is upset by a ram pressing said bar section against the upsetting means, and in which the 10 deforming step takes place at a second station at which said upset bar section is introduced axially between co-operating male and female die halves.

5. Process as defined in claim 1, in which at least said female die half is sprayed with a coolant immediately 15 after said shaped component has been ejected from said female die half, and in which said coolant is sprayed from at least one bore provided in an ejector pin associated with said female die half.

6. Apparatus as defined in claim 2, further comprising

(i) spraying means for spraying at least one die of said co-operating dies with a coolant.

7. Apparatus as defined in claim 2, further comprising a burr removal station having male and female punching dies, an ejector mounted in the female punching die, a retaining pin for retaining the shaped component against said female punching die after said male punching die has sheared-off each burr, and a second retaining pin for each burr to be punched off 30 mounted for movement parallel to said male punching die, each second retaining pin adapted to hold its associated burr against said female punching die during and after the shearing operation.

8. Apparatus as defined in claim 2, in which the ejector in said female die half has a blind aperture bore therein connected to a coolant source, at least one passage bore in the wall of the ejector pin extending practically transversely of said blind aperture bore and debouching into the same, to serve for outflow of the coolant on to said shaped end of the female die half.

9. Apparatus as defined in claim 8, further comprising a resilient means which is adapted to retract said ejector after it has reached the forward dead-center position on the front edge of said shaped end of said female die half.

10. Apparatus as defined in claim 9, in which said resilient means is a cup spring assembly and in which said ejector has a collar which is rigidly connected therewith and which is adapted, towards the end of the ejection movement to impinge on the cup spring assembly and biases the latter.

11. Apparatus as defined in claim 2, in which said ejector has a cylindrical section formed with a cooling bore and a sleeve mounted for sliding at the periphery of the said section; and in which the sleeve is connected, via two ejector pins of different diameters, and arranged one behind the other in a stepped bore, with an actuating rod, said smaller diameter pin projecting, before the commencement of the ejection step, by a predetermined amount into a bore of said thicker ejector pin, whereby due to the movement of said actuating rod, first of all only said sleeve is advanced by said predetermined amount and then said sleeve and said cylindrical section are advanced by a further amount.
